(57) **CLAIM**

We claim the ornamental design for a set of wheel chocks, as shown and described.

DESCRIPTION

FIG. 1 is a front perspective view of a right wheel chock. FIG. 2 is a rear perspective view of the right wheel chock. FIG. 3 is a front perspective view of a left wheel chock which is a mirror image of the left wheel chock shown in FIG. 1. FIG. 4 is a rear perspective view of the left wheel chock which is a mirror image of the left wheel chock shown in FIG. 2. FIG. 5 is a top plan view of the right wheel chock. FIG. 6 is a right side elevation view of the left wheel chock. FIG. 7 is front elevation view of the right wheel chock. FIG. 8 is a rear elevation view of the right wheel chock. FIG. 9 is a left side elevation view of the right wheel chock. FIG. 10 is a bottom plan view of the right wheel chock; and, FIG. 11 is a perspective view of a left wheel chock and a right wheel chock, each with a raised wheel retainer.
